CONTROL SYSTEM FOR RAILWAY TRAFFIC
CONTROLLING DEVICES

Oscar S. Field, Rochester, N. Y., assignor to General Railway Signal Company, Rochester, N. Y.

Application February 25, 1932, Serial No. 595,131

13 Claims. (Cl. 246—3)

The present invention relates to control systems for railway traffic controlling devices and more particularly to a means for controlling a multiple aspect color light signal and for accurately indicating the aspect displayed by such signal at a central control point such as an interlocking tower.

In controlling railway traffic control devices from a central point such as in an interlocking system it is found economical and desirable to operate such traffic controlling devices from an alternating current source at places where a reliable supply of such current is available. In such control systems it is also essential to have an accurate indication that the signal is actually displaying an aspect which corresponds to the position of the control lever in as much as train operation may be endangered by the movement of an associated traffic control device, such as a switch or derail, at times when the signal is not displaying a restricted indication.

In view of the above and other considerations it is proposed in accordance with the present invention to provide a signal control circuit which is operable from an alternating current source and by which an accurate indication may be received not only of the character of the displayed aspect but also of the actual display of such signal aspect.

Other objects, purposes and characteristic features of the invention will appear as the description thereof progresses, during which references will be made to the accompanying single figure of drawing which diagrammatically shows a circuit for controlling a multiple aspect color light signal in accordance with this invention.

In this drawing a signal control lever L is shown as being operable to two distinct positions R and Y and has associated therewith an indicating relay IR and an indicating lamp I has been diagrammatically shown as typical of a function which this relay may perform. A signal mechanism has been diagrammatically shown in the dotted rectangle S and may be of the type shown in my prior application Ser. No. 470,056 filed June 23, 1930.

The signal mechanism here illustrated is of the two-aspect type having a movable vane mechanism 1 which holds two distinctively colored spectacles of r and y and this vane is biased by a counter-weight 2 to a center position in which the red spectacle r aligns with a signal lamp SL. An operating winding W is provided which when energized is adapted to attract the lower end of the vane 1 to a position in which the yellow

spectacle y aligns with the signal lamp SL. A contact 3 is operated by the movement of this vane 1 through an arm 4 to make up either back point 5 or front point 6 according to the position of the vane 1.

In as much as these signal mechanisms S are designed for direct current operation, it is found desirable to insert a rectifying unit 7 in series with the operating winding W to obtain satisfactory operation of the vane 1 but it is obvious that with mechanisms designed for alternating current operation it may be omitted. A source of alternating current supply is indicated as being received from a transformer T and a wire C leading therefrom is the common wire for the signal S and may be extended throughout the system as a common wire to other mechanisms which are similarly controlled. The signal lamp SL is energized from a secondary winding of a lighting transformer LT which has a primary winding in series with the circuit for indicating a restrictive signal indication as will be later described.

The signal lever L is illustrated as assuming a position R in which it conditions the signal mechanism S to display a red, the most restrictive, indication in as much as the winding W is not energized to attract the vane 1 and it assumes its biased center position in which the red spectacle r aligns with the signal lamp SL. An indication of this display of a red indication is obtained by the energization of the indicating relay IR as follows:—beginning at the secondary winding of the transformer T wire 9, lever contact 10 in its left hand position, wire 11 through the winding of relay IR, wire 12, signal contact 3 made at its back point 5, wire 13, through the primary winding of transformer LT, wires 14 and 15 to the common wire C and back to the other side of the secondary of the transformer T. The indication obtainable from the indicating relay IR may be employed in any manner to suit the requirements of the particular system such as the locking of conflicting control levers, but herein has been shown as energizing an indicating lamp I over an obvious circuit made at front contact 16 of the relay IR.

Now considering that it is desired to operate the signal S to display a less restrictive indication the signal lever L is operated to a position Y and a circuit is then made up to energize the winding W as follows:—beginning at the secondary of the transformer T, wire 9, lever contact 10 in its right hand position, wire 18, contact 19 of relay IR which is now de-energized in as much as its circuit is broken by contact 10 moving

ing to its right hand position thereby completing the circuit from this contact 19 to wires 20 and 21, through the rectifier 7 and the operating winding W, wire 15 to the common wire C and back 5 to the transformer T.

The energization of the winding W moves the vane 1 as previously stated, to a position in which the spectacle y aligns with the signal lamp SL and the contact 3 is of course operated to a left 10 hand position by this movement of the vane 1. A circuit for energizing the lighting transformer LT is again completed which is in parallel with the operating winding W and may be traced from the energized wire 20 through wire 22, a resistor 15 23 wire 24 through back point 6 and contact 3, wire 13 primary of the lighting transformer LT, wires 14 and 15 to the common wire C. This energizes the signal lamp SL from the secondary of this lighting transformer LT the same as in 20 displaying the red indication but in as much as the yellow spectacle y is now in a position aligning with the signal lamp SL the yellow indication is displayed and the display of this less restrictive 25 signal aspect is controlled, and hence is indicated at the control point, by the de-energization of the indicating relay IR provided, of course, that the described circuits are intact. The resistor 23 is provided in the signal lighting circuit in this 30 case to compensate for the resistance of the windings of relay IR which is inserted in this circuit during the display of a red indication. The lighting circuit is then of the same resistance in either 35 case which maintains equal intensity of signal indications.

35 It is now obvious that an accurate check on the display of the most restrictive or the red indication of the signal mechanism S is obtained by providing the contact 3 in series therewith which directly checks the character of the aspect 40 through the position of the vane 1. A further check is obtained on the presence of signal light in as much as a condition in which this signal lamp does not draw current from the secondary 45 of the lighting transformer LT, such as may be brought about by a burned out filament, sufficiently increases the impedance of the primary to reduce the current in the indicating relay IR to a degree effecting the opening of its contact 16 50 and thereby preventing a false indication at the control point.

The present invention also contemplates a means for preventing a false indication due to an out-of-correspondence condition between the signal mechanism S and the control lever L which 55 may be brought about by a cross or short circuit between the control wires 12 and 20. For example, a circuit energizing the winding W of the signal mechanism to give a yellow indication 60 when the control lever L is in its red or R position may be completed due to a cross as follows:— from transformer T, wire 9, lever contact 10 in its left hand position, wire 11, windings of relay IR, wire 12 through a short circuit or cross to 65 wire 20, wire 21, rectifier 7, operating winding W, wire 15, common wire C back to transformer T.

70 It will be noted in the above circuit that the winding of the relay IR is in series with the operating coil W of the signal mechanism and consequently if this coil W is arranged to present sufficiently greater impedance to this circuit than is offered by the lighting transformer LT under normal conditions, the current value of this cross circuit will be reduced to a point ineffective to 75 cause opening of contacts 3—5 and consequently

the correct indication of the signal aspect will remain at the control point.

A system for controlling a color light signal has thus been provided which is adaptable to use in an interlocking plant where it is found desirable 5 to employ alternating current for operation and which provides an indicating means which is sufficiently reliable to meet the requirements of the interlocking between other conflicting control levers. 10

The above rather specific description of one form of the present invention is given solely by the way of example and not intended in any manner whatsoever in a limiting sense. It is also to be understood that various modifications, adaptations and alterations will be supplied to meet the requirements of practice without in any manner departing from the spirit or scope of the present invention except as limited by the appended 15 claims. 20

Having thus described my invention, what I claim is:—

1. In a manually controlled signal system for railroads, a color light signal mechanism biased to display a most restricted indication, an electric 25 light source for the signal mechanism, a control lever for said signal mechanism, energizing means including an alternating current rectifying unit for operating said signal mechanism to display a less restricted indication in accordance with the position of said control lever, and means for energizing a relay when said signal mechanism displays a most restricted indication in correspondence with said control lever, and only when current flows in the light source of said 30 signal mechanism. 35

2. In a manually controlled signal system for railroads, a signal mechanism biased to display a most restricted indication, a control lever for said signal mechanism, a lever contact, energizing means including an alternating current rectifying unit for operating said signal mechanism to display a less restricted indication in accordance with the position of said control lever, and a circuit, including the lever contact, for energizing a relay effective when said signal mechanism displays a most restricted indication in correspondence with said control lever. 40 45

3. In a signal control system, a multiple aspect signal mechanism normally displaying a danger 50 signal, an indicating relay, a control lever, a lever contact, circuit means controlled by said relay and by said control lever for operating said signal mechanism to display a less restricted indication, contact means operated by said signal 55 mechanism in accordance with the character of the signal, and a circuit, including the lever contact and signal mechanism contact means, for energizing said relay when said signal mechanism contact is in correspondence with said control lever contact. 60

4. In a signal control system, a signal lamp, a transformer having a secondary winding supplying current to said signal lamp, a manually controlled signal mechanism operable to variously 65 cooperate with the signal lamp to thereby display a plurality of signal aspects, an indicating relay, and an energizing circuit for said relay including a primary winding of said transformer arranged to open said indicating relay contacts 70 when the impedance of the primary winding is increased by the cessation of flow of current in the secondary winding. 75

5. In a signal control system, a single signal lamp, a signal mechanism arranged to determine 75

- the color of indication displayed by said lamp, means biasing said signal mechanism to display a red indication, power operated means for moving said signal mechanism to a position for displaying a yellow indication, a control lever, a signal indicating relay, a source of alternating current energy, a circuit energizing said signal mechanism operating means from said source of energy including a back contact on said indicating relay and controlled by said control lever, an energizing circuit for said signal lamp including contacts made when said signal mechanism is in said yellow signal position and an energizing circuit for said indicating relay in series with a lighting means for said signal lamp including contacts made by said signal mechanism in its biased position and contact means operated by said control lever.
6. Signal control circuits comprising a movable signal mechanism and a light source, manually operable means for controlling the aspect displayed by said signal mechanism, and signal indicating means arranged to check the correspondence between the position of said manually operable means and the aspect displayed by said signal mechanism and the energization of the light source.
7. In a signal control system, a multiple aspect signal mechanism including a light source and normally displaying a danger signal, an indicating relay, a control lever, circuit means controlled by said relay and by said control lever for operating said signal mechanism to display a less restricted indication, contact means operated by said signal mechanism in accordance with the character of the signal, and a circuit energizing said relay when said signal mechanism is positioned to display a danger indication in correspondence with said control lever and only when the light source is intact.
8. In a signal control system, in combination, a light signal having a light source and a co-operating spectacle, a spectacle contact movable by the spectacle, a remote control lever for the signal, an indication relay controlled by the lever and the spectacle contact and energized when the lever and spectacle contact are in correspondence with the signal giving its most restrictive indication.
9. In a signal control system, in combination, a light signal having a light source and a co-operating spectacle, an operating winding for the spectacle, an energizing winding for the light source, a spectacle contact movable by the spectacle, a remote control lever, an indication relay controlled by the lever and the spectacle contact and energized when the lever and spectacle contact are in correspondence with the signal giving its most restrictive indication, the energizing circuit for the indication relay including said energizing winding, the energizing circuit for said operating winding including a back point of the indication relay and a lever contact when the lever is in a position corresponding to a less restrictive signal indication.
10. In a signal control system, in combination, a light signal having a light source and a co-operating spectacle, an operating winding for the spectacle energizable over a control wire, an energizing winding for the light source, a spectacle contact movable by the spectacle, a remote control lever, an indication relay controlled by
- the lever and the spectacle contact over an indication wire and energized when the lever and spectacle contact are in correspondence with the signal giving it most restrictive indication, the energizing circuit for the indication relay including said energizing winding, the energizing circuit for said operating winding including a back point of the indication relay and a lever contact when the lever is in a position corresponding to a less restrictive signal indication, the impedance of the said operating winding being greater than that of the said energizing winding, whereby a cross between the control and indication wires, when the signal is giving its most restrictive indication, energizes the operating winding in series with the indicating relay to an extent insufficient to operate the spectacle.
11. In a signal control system, in combination, a light signal having a light source and a co-operating spectacle, an operating winding for the spectacle energizable over a control wire, an energizing winding for the light source, a spectacle contact movable by the spectacle, a remote control lever, an indication relay controlled by the lever and the spectacle contact over an indication wire and energized when the lever and spectacle contact are in correspondence with the signal giving it most restrictive indication, the energizing circuit for the indication relay including said energizing winding, the energizing circuit for said operating winding including a back point of the indication relay and a lever contact when the lever is in a position corresponding to a less restrictive signal indication, the impedance of the said operating winding being greater than that of the said energizing winding, whereby a cross between the control and indication wires, when the signal is giving its most restrictive indication, energizes the operating winding in series with the indicating relay to an extent insufficient to operate the spectacle.
12. In a signal control system, in combination, a light signal having a light source and a co-operating spectacle positionable to give different indications, a spectacle contact movable by the spectacle, a remote control lever for the signal for controlling the spectacle, an indication relay controlled by the lever and the spectacle contact and energized only when the lever and spectacle contact are in correspondence with the signal giving its most restrictive indication.
13. In a signal control system, a multiple aspect signal mechanism normally displaying a danger signal, in indicating relay, a control lever, a lever contact, circuit means controlled by said relay and by said control lever for operating said signal mechanism to display a less restricted indication, contact means operated by said signal mechanism in accordance with the character of the signal, and a circuit, including the lever contact and signal mechanism contact for energizing said relay when said signal mechanism contact is in correspondence with said control lever contact and then only when the mechanism is positioned to display a danger indication.
